UNITED STATES PATENT OFFICE.

ALFRED W. FRENCH, OF PIQUA, OHIO.

PRESS-PLATE.

1,355,136.

Specification of Letters Patent. Patented Oct. 12, 1920.

Application filed September 16, 1918. Serial No. 254,242.

To all whom it may concern:

Be it known that I, ALFRED W. FRENCH, a citizen of the United States, residing at Piqua, in the county of Miami and State of Ohio, have invented a new and useful Improvement in Press-Plates, of which the following is a specification.

This invention relates to press plates more particularly intended for use in oil expressing presses of the so-called "cage press" type in which cakes or charges of meal separated by press plates and cloths are subjected to pressure in an open-ended press cage having orifices in its side walls for the escape of the expressed oil.

The objects of the invention are to provide a practical and desirable press plate, especially suitable for cage presses, which is of simple, inexpensive and durable construction, and which will insure ready and complete drainage through the plate for the escape of oil from the material in the cage to the edges of the press plates or to the side walls of the cage; also to construct the press plates so that while they can be produced from sheet metal at a moderate price, nevertheless the plates will not be deformed or their drainage channels constricted by the pressure to which the plates are subjected in use.

In the accompanying drawings:

Figure 1 is a plan view of a press plate embodying the invention, a portion of one of the component plates being broken away to show the underlying parts.

Fig. 2 is a similar view showing a portion of the plate substantially full size.

Fig. 3 is a fragmentary bottom plan view thereof.

Figs. 4 and 5 are sections thereof on lines 4-4 and 5-5, respectively, Fig. 2.

The press plate is composed of two pieces of sheet metal or thin metal plates A and B arranged face to face or one flat upon the other, and preferably, though not necessarily, secured rigidly together in some suitable way, as for instance by rivets 10 at the corners of the plates. The two plates thus connected can be easily separated if necessary, for cleaning out their holes and channels, hereinafter described, or for any other reason by cutting the rivets, and the plates can be again riveted together with little labor and expense. The press plates can be either rectangular, as shown, or of any suitable shape and size, depending upon the

presses or cages with which they are to be used.

One of the plates, A, is provided at suitable intervals with bends or corrugations 11 on one side of the plate, and grooves or channels 12 which, when the two plates are placed or secured together face to face, form oil drainage or flow channels between the plates. The other plate B is preferably flat or has opposite plain flat surfaces and is provided with small holes or perforations 13 through it. These holes, which may be cylindrical or of any other suitable form, are preferably disposed in rows opposite or in line with the drainage channels 12 so that the oil or liquid expressed from the material in the press between the press plates can readily escape through the holes 13 into the drainage channels and flow through these channels to the edges of the press plate or to the side walls of the press cage. The plate A is preferably imperforate. The top surface 14 of the press plate is preferably polished so that the press cloths will not stick to the plates, and the bottom surface 15 of the plate is likewise preferably polished to prevent the meal from adhering thereto. This materially facilitates the removal of the press cloths and plates from the press, because in unloading the press the cakes, cloths and plates are removed one at a time as they are shoved out of the upper end of the cage by the ascent of the press ram, and when a cake has been removed the underlying cloth can be easily shoved or slid horizontally off of the smooth polished top surface of the press plate beneath it without having to forcibly strip or pull off the cloth as is usually necessary, and after the cloth has been thus removed the press plate can be easily lifted off of the next cake since the polished under surface of the plate will not adhere to the underlying cake. No press cloths are necessary between the upper surfaces of the cakes and the undersides of the press plates constructed as described.

16 represents wires or rods extending lengthwise in the drainage channels 12 between the plates A and B. These wires act as plate-spacing or supporting members which prevent the flattening out of the ribs 11 and the crushing in of the plate B over the drainage channels so as to constrict the drainage channels and interfere with the free drainage of the oil through the same.

While, therefore, relatively thin metal plates or sheets A and B can be employed in making the press plates, there is no danger of the press plates being crushed and the channels constricted under the pressure to which the press plates are subjected in use. The wires 16 are preferably secured in place by bending up the ends thereof and riveting these bent ends in holes in the plate B, as indicated at 17, Fig. 5. The spacing wires 16 will not close the drainage holes 13 in the plate B enough to interfere with a free escape of oil through the holes, even if the holes are located directly above the wires, but the holes can be, if desired, arranged at one side of the wires, so as not to be obstructed at all by the wires.

I claim as my invention:

1. A press plate comprising two thin metal plates arranged face to face, one of said plates having spaced corrugations forming hollow projecting ribs on the outer side of said plate and drainage channels on the inner side of the plate and said other plate being flat and having holes through which liquid can escape to said drainage channels.

2. A press plate comprising sheet metal plates arranged face to face, one of said plates having transverse bends therein forming hollow ribs which project from the outer side of said plate and provide drainage channels between the two plates, and said other plate having a substantially flat, smooth outer face and having holes through which the liquid can escape to said drainage channels.

3. A press plate comprising two thin metal plates arranged face to face, one of said plates having bends forming hollow imperforate projecting ribs on one side of said plate and drainage channels between the two plates, and said other plate having holes through which liquid can escape to said drainage channels.

4. A press plate comprising two sheet metal plates arranged face to face, one of said plates having bends forming hollow imperforate projecting ribs on the outer side of said plate and drainage channels on the inner side of the plate, and said other plate being flat and having holes through it in line with said drainage channels through which liquid can escape to said drainage channels.

5. A press plate comprising two thin metal plates arranged face to face, one of said plates having spaced corrugations forming hollow projecting ribs on one side of said plate and drainage channels between the two plates, and one of said plates having holes through which liquid can escape

to said drainage channels, and plate-spacing members located between said plates in said channels for preventing constriction of the channels.

6. A press plate comprising two plates arranged face to face and having drainage channels formed between the plates, one of said plates having holes through which liquid can escape to said drainage channels, and plate-spacing members located between said plates in said channels for preventing constriction of said channels.

7. A press plate comprising two plates arranged face to face and having drainage channels formed between the plates, one of said plates having holes through which liquid can escape to said drainage channels, and wires extending lengthwise in said channels for preventing constriction of said channels.

8. A press plate comprising two plates arranged face to face and having drainage channels formed between the plates, one of said plates having holes through which liquid can escape to said drainage channels, wires extending lengthwise in said channels, and means for securing said wires.

9. A press plate comprising two plates arranged face to face, one of said plates having bends forming hollow projecting ribs on one side of said plate and drainage channels between the plates, one of said plates having holes through which liquid can escape to said drainage channels, and wires extending lengthwise in said channels between said plates.

10. A press plate comprising two plates arranged face to face, one of said plates having bends forming hollow projecting ribs on one side of said plate and drainage channels between the plates, and said other plate being flat and having holes through which liquid can escape to said drainage channels, and wires extending lengthwise in said channels between said plates.

11. A press plate comprising two plates arranged face to face, one of said plates having bends forming hollow projecting ribs on one side of said plate and drainage channels between the plates, one of said plates having holes through which liquid can escape to said drainage channels, and wires extending lengthwise in said channels between said plates, said wires having bent ends secured in holes in one of said plates.

Witness my hand, this 10 day of September, 1918.

ALFRED W. FRENCH.
